UNITED STATES PATENT OFFICE.

GEORGE W. ELTZROTH AND ISAAC RAYPHOLTZ, OF MARION, INDIANA.

CAR-COUPING.

SPECIFICATION forming part of Letters Patent No. 267,850, dated November 21, 1882.

Application filed August 23, 1882. (No model.)

To all whom it may concern:

Be it known that we, GEORGE W. ELTZROTH and ISAAC RAYPHOLTZ, of Marion, in the county of Grant and State of Indiana, have invented certain new and useful Improvements in Car-Couplings; and we do hereby declare that the following is a full, clear, and exact description of the invention, which will enable others skilled in the art to which it appertains to make and use the same, reference being had to the accompanying drawings, which form a part of this specification.

This invention relates to car-couplings, and has for its object to provide simple, durable, inexpensive, and efficient means for coupling the cars automatically and uncoupling without going between the cars.

In the drawings, Figure 1 is a perspective view of the end of a car equipped with our improved coupling. Fig. 2 is a vertical longitudinal sectional view. Fig. 3 is a top view of the draw-head proper. Fig. 4 is a front view thereof. Fig. 5 is a transverse sectional view on the line $x x$, Fig. 3.

Referring to the drawings, A designates the draw-head, which is formed with the usual mouth, B, link-recess C, vertical pin-perforation D, and is capable of longitudinal movement by means of a rear spring, E, or other suitable means. In rear of perforation D, and in its top, the draw-head is provided with a longitudinal slot, F, connected with perforation D by a groove, G, as shown. At the bottom of the draw-head, in front of its rear wall, H, is secured a right-angular flat spring, I, comprising the vertical arm J and horizontal top arm, K. Spring I works at the vertex of the angle in slot F, while its arm K moves in groove G, its circularly-notched end L normally extending over perforation D. On top the draw-head is secured an upright standard, M, having a bearing, N, at its top for the upper half, O, of the coupling-pin P and an extension, Q, at its bottom. Extension Q is preferably formed by a plate, as shown, which extends forwardly and horizontally, and is some distance above the top surface of the draw-head, said plate being provided with bearings R for the lower half of pin P. The

latter is provided or formed at or near its center with an annular shoulder or flange, S, which supports the pin when down and limits its vertical movement, so that it will not be entirely withdrawn from the draw-head.

T is a spring-supporting bracket or rest, arranged to extend in front of the draw-head, the latter being provided with openings U in each side. In one opening is pivoted the end V of the wire forming the apron, the latter being constructed of one piece of spring-wire. From the end V the wire is continued to form side bar W, thence across to form the rest X, and again up to form the side bar Y, at the top of the latter being provided a coil, Z, the end of which, A', passes through the opening U, and is bent over as shown. When the rest is down the end A' bears against the top of the draw-head, and the rest will "give," by reason of coil Z, to any weight. At the same time the rest can be thrown up out of engagement to the position shown in dotted lines. The cross-bar X is preferably flattened, as at B' B', and serves to support the link when entering the adjoining draw-head.

C' is an additional stop for the coil Z. To provide for elevating the pin without going between the cars, it is connected at its top by a chain, a; to the arm b of a cross-rod, c, journaled in bearings d d at the end of the car, and provided at its outer end with an operating arm or handle, e. A chain, f, also extends from arm b to the top of the car.

The operation and advantages of my invention will be readily understood. When the pin is elevated the spring I moves forward until its end L passes under the pin, which is thus supported in an elevated position. Now, when the link of the adjoining car enters the draw-head it strikes spring I and forces it back, allowing it to fall and effect the coupling. By reason of the curved end of the spring I it requires but a slight movement to effect its disengagement from the pin.

We claim as new—

1. The combination of the draw-head having perforation D, longitudinal slot F in its top, and intermediate groove, G, the upright standard having bearing N at its top and an

elevated front extension at its bottom, provided with bearing R, the right-angular flat spring arranged in rear of the link-recess and having circularly-notched end L, and the coupling-pin, having an about midway flange or shoulder, S, as set forth.

2. The herein-described rest or bracket T, having end V, central cross-bar X, provided with flattened portions B', and end Z, formed by a circular coil, as shown.

In testimony that we claim the foregoing as our own we have hereto affixed our signatures in presence of two witnesses.

GEORGE W. ELTZROTH.
ISAAC RAYPHOLTZ.
